UNITED STATES PATENT OFFICE

169,968

CAP

Samuel Feldman, New York, N. Y.

Application June 3, 1952, Serial No. 20,004

Term of patent 14 years

(Cl. D3—13)

To all whom it may concern:

Be it known that Samuel Feldman, a citizen of the United States of America, and resident of the city, county and State of New York, has invented a new, original, and ornamental Design for a Cap, of which the following is a specification, reference being had to the accompanying drawing forming part thereof, in which

Fig. 1 is a front elevational view of a cap embodying my new design;

Fig. 2 is a top plan view thereof;

Fig. 3 is a side elevational view thereof; and

Fig. 4 is a rear elevational view thereof.

I claim:

The ornamental design for a cap, substantially as shown.

SAMUEL FELDMAN.
